UNITED STATES PATENT OFFICE.

EUGENE PRINGLE, OF GLOVERSVILLE, NEW YORK, ASSIGNOR TO MADISON D. SHIPMAN AND CHARLES E. BRADT, BOTH OF DE KALB, ILLINOIS.

SEPARABLE BUTTON.

SPECIFICATION forming part of Letters Patent No. 447,347, dated March 3, 1891.

Application filed September 8, 1888. Serial No. 284,942. (No model.)

To all whom it may concern:

Be it known that I, EUGENE PRINGLE, a citizen of the United States, residing at Gloversville, in the county of Fulton and State of New York, have invented certain new and useful Improvements in Separable Buttons, of which the following is a specification.

My invention relates to improvements in separable buttons; and it consists in the devices and parts and combinations of devices and parts hereinafter described, and specifically set forth in the claims.

The objects of my invention are, first, to combine with a head of a separable button an elastic stud-catch, a stud-catch-supporting piece, and a stud-catch-binding piece for operating with the outer ring-form portion of the catch; second, to provide in a button-head of a separable button a combination of an elastic stud-catch, (having a ring-form outer portion and a catching-limb made integral with said ring portion and relatively tangent to the circumference of the coacting stud,) a catch-supporting plate, a binding-piece resting on the upper side of the ring-shaped portion of the stud-catch, and a clamping-piece which will hold the binding-piece and supporting-piece clamped against the opposite sides of the ring portion of said catch; third, to provide, in a head of a separable button a stud-catch which has a ring-form outer portion, two plates binding the said ring-form portion with the catching-limb free, a clinching device which will bind the piece acting on the ring-form portion of the catch with the same, and a button-head - closing piece provided with an eyelet for co-operation with a piece inclosing the elastic spring-stud catch; fourth, to provide in a separable button the combination, with an elastic stud-catch, of two pieces for clamping the ring portion of said catch, a clamping-shell and an outer inclosing shell for clamping on the upper side of the material, and an eyelet which will unite the clamping-piece and shell with the pieces which clamp the stud-catch and the material on its under side; fifth, to provide in a separable button the combination, with the shell-form stud and a clamping-washer, of an eyelet connected with the stud and a closing-piece connected with the washer, whereby the

stud will be secured to the material; sixth, to provide in a separable button, and in combination with the closing plate or piece attached to the washer which co-operates with an eyelet for securing the stud to the material, a non-metallic covering applied to the wear side of the closing-piece, whereby the face side of the piece will have a non-metallic wearing-surface. I attain these objects by the means illustrated in the accompanying drawings, forming a part of this specification, in which—

Figure 1 is a sectional elevation of the button-head and stud of a separable button. Fig. 2 is a plan view of the piece which supports the elastic stud-catch. Fig. 3 is a sectional view of the same. Fig. 4 is a plan view of my improved elastic stud-catch. Fig. 5 is a sectional view of the same. Fig. 6 is a plan view of one form of piece which can be employed for clamping the elastic spring-catch in place. Fig. 7 is a sectional view of the same. Fig. 8 is a plan view of a clamping-piece which can be employed for holding the elastic stud-catch-holding piece and top clamping-piece in place on the stud-catch. Fig. 9 is a sectional elevation of the same. Fig. 10 is a plan view of a form of an eyelet which can be employed to connect the shell of the button-head with the stud-catch-holding device and clamping the material. Fig. 11 is a sectional elevation of the same. Fig. 12 is a plan view of the outer inclosing shell of the button-head. Fig. 13 is a sectional view of the same. Fig. 14 is a sectional elevation showing modified forms of some of the parts which can be used in the button-head for holding the elastic stud-catch in place and in connection with the outer shell. Fig. 15 is a sectional elevation which illustrates other modifications of the same. Fig. 16 is a sectional view illustrating modifications of other parts. Fig. 17 is a sectional elevation of the stud and eyelet connected together before attachment to the material. Fig. 18 is a sectional view of the clamping-washer and eyelet-spreading piece connected with the same before attachment to the coacting stud. Fig. 19 is a plan view of the clamping-piece holding the stud connected with the eyelet. Fig. 20 is a sectional view of the same before being secured to the attaching-eyelet. Fig. 21

is a sectional view of the stud before attachment to the eyelet. Fig. 22 is a plan view of the same. Fig. 23 is the attaching-eyelet employed with the stud. Fig. 24 is a plan view 5 of the same. Fig. 25 is a sectional view of the clamping-washer. Fig. 26 is a plan view of the same. Fig. 27 is a sectional view of the eyelet-spreading piece before its connection with the clamping-washer and the non-metallic covering to the same before the connection of the said piece and clamping-washer. Fig. 28 is a plan view of the same.

The same letters of reference refer to like parts throughout the several views.

5 In the drawings, A represents a plain circular piece for supporting the elastic stud-catch B from its lower side. This piece is shown in Fig. 2 to be in the form of a plain disk having a central perforation a. In Fig. 15 this disk A is shown to have made with it a clinching-flange a'.

B is the elastic stud-catch, made of wire, bent so as to produce the ring-form portion b and an internal coil b', continued from the 25 ring portion b to the catching-limb b² and all integral, as shown in Fig. 4. This elastic stud-catch B thus formed rests on the supporting-piece A, as shown in Figs. 1, 14, 15 and 16.

30 C is the top side binding-piece of the elastic stud-catch A, and is shown in Figs. 1, 6, and 7 to be made with a dome-shaped top c and bearing-rim c'. When in position, as shown in Fig. 1, this rim portion c' will have 35 bearing on the ring-form portion b of the stud-catch, as shown in Fig. 1.

In Fig. 14 piece C' is employed as a substitute for piece C (shown in Figs. 1, 6, and 7) and operates the same as to the purpose of 40 clamping on the upper side of the ring-form portion b of the spring-catch B, and in Fig. 15 the piece C² operates substantially for the same purpose.

In Fig. 16 the piece C³ is shown to operate 45 for the same purposes as piece C in Figs. 1 and 7 and as pieces C' C² in Figs. 14 and 15, while at the same time this piece C is shown to have made with it a clinching-rim c² for binding piece A against the lower side portion 50 b of the elastic stud-catch B.

D is a piece for holding the piece A in place against the lower side of the stud-catch, and also for holding with an eyelet for connecting the outer shell of the button-head with 55 the parts holding the stud-catch.

E is the clamping-eyelet, having its flange e made with a curved form (or form corresponding with the outer shell) and its portion e' extending from the apex of this curved 60 flange downwardly, as shown in Fig. 11.

F is the outer or inclosing shell. This shell F is secured to piece E by clinching, as shown in the several figures, and incloses all the parts of the button-head contained within the 65 same.

In Fig. 15 the piece E' is substituted for the piece E, (shown in Figs. 1, 10, and 11,) and it

operates with the shell F and piece C to hold the parts which inclose the stud united with said shell F and also clamping with the material. 7c

In Fig. 15 the dome portion c (of the top side binding-piece) of the stud-catch is omitted, and in lieu thereof there is employed the piece c³ for spreading portion of C², which operates as an inverted eyelet for holding the upper clamping-shell with the stud-catch-supporting piece. At the same time it operates as a binding-piece on the upper side of portion b of the stud-catch B. The eyelet portion of this piece C², Fig. 15, is shown to be spread outwardly on the internal flange e by the piece c³. In Fig. 16 the piece designated as C³ (and which operates the same as C² in Fig. 15 and as a piece for binding on the upper side of the ring portion b of the stud-catch B) is shown to be clinched on the lower side of the spring-catch piece A. In these modifications shown in Figs. 1, 14, 15, and 16 the essential features of the stud-catch B and the pieces or devices for clamping the rim portions b of the same from both its lower and upper sides are substantially the same, and the outer shell portion and outer piece clamping on the material are also 95 substantially the same, while the pieces forming the binding or clinching eyelet and which hold the outer shell portions, with the part, holding the stud-catch, differ in form, though operating to effect substantially the same results. 100

G is the stud, made with ball form of head g and base-flange g'.

H is an eyelet having its flange h set against the lower side of base g' and secured thereto 105 by clinching device I or by a clinching-rim made with the flange g' of the stud or with the flange h of eyelet H.

J is a clamping-washer for coaction with eyelet H to secure it to the fabric. This 110 washer is made with a concave form of body, as shown in Figs. 18 and 25.

K is the washer-backing piece, having with it the clinching-rim k and eyelet-spreading portion k'. (Shown in Figs. 18 and 27.) 115

L is a non-metallic covering applied to the lower side of the washer-backing piece K. This covering L, when turned and secured as shown in Fig. 18, operates as a wearing-face to prevent the metal of the washer-backing 120 piece K from marking or soiling the wrists of the wearer of the glove.

By my above-described improvements the button-head portion and stud portion of the separable button can be cheaply produced and 125 be made, respectively, to have a secure holding with the material and with each other.

What I claim as new is—

1. In a separable button, the combination of the spring B, having the outlying ring-form 130 portion b, the inner central portion b', and the stud-engaging arm b², with the plate A, having a stud-receiving opening, a second outwardly-flanged piece, said pieces interlocked

at their outer margins and firmly clamping the said outlying ring-form portion *b* of the spring, and a clinching-tube for securing all of the above parts to the button-cap and fabric, substantially as and for the purpose set forth.

2. In the button-head of a separable button, the combination of the stud-catch *B*, held in place within the button-head by an outlying ring-form portion, the stud-catch-supporting piece having the perforation *a*, and an upper side binding-piece securing the outlying portion of the stud-catch *B* and said perforated supporting-piece with the outer shell of the

button-head, substantially as and for the purpose set forth. 15

3. In a separable button, the combination, with a shell-form stud provided with a base-flange and an eyelet secured by its flange with the flange of said stud, of the holding-washer 20 and washer-backing piece secured to said washer, substantially as and for the purposes set forth.

EUGENE PRINGLE.
